HIRAM L. HENDERSON, OF SYRACUSE, NEW YORK

DRY KILN

Application filed May 31, 1929. Serial No. 367,372.

This invention relates to a dry-kiln adapted to be used more particularly for a drying lumber which has been stacked upon a suitable support within the kiln in such manner 5 is to enable the heat to circulate between the several layers.

The main object of the present invention is to effect a more thorough seasoning and drying of the lumber or other material within a 10 shorter period of time than has heretofore been practiced.

In some instances heated air alone has been used for drying lumber, but this method requires a considerable period of time and 15 results, in many instances, in merely drying the surface of the lumber without penetrating to the interior of the several pieces thereby causing more or less warping, checking or splitting of the lumber without thoroughly 20 drying and seasoning of the same.

Furthermore, this hot air drying in some instances has been supplemented by the introduction of moisture such as steam to mingle with the heated air and to circulate therewith 25 through the lumber stack for the purpose of effecting more thorough seasoning and drying of the lumber, but in most instances with which I am familiar, the circulation of the moisture-laden air by an individual blower 30 has been maintained in one direction only throughout the drying operation so that if a uni-directional current is used, the drying operation must be continued for a longer period of time than would be required if the direction 35 of circulation were intermittently varied, resulting in excessive surface drying and consequent warping, checking and splitting of the lumber before the interiors of the several pieces has been thoroughly dried.

One of the specific objects, therefore, of the present invention is to avoid these objectionable results by providing means whereby the direction of flow of the air currents may be 40 changed at suitable intervals so as to not only cause a more thorough seasoning and drying of all parts of the lumber but also to expedite the seasoning and drying operations so that a better quality of the finished product may 45 be turned over in a shorter period of time.

and with considerably less carrying cost than has heretofore been practiced.

Other objects and uses relating to the specific parts of this kiln will be brought out in 55 the following description.

In the drawings:—

Fig. 1 is a transverse vertical sectional view of a dry-kiln embodying the various features of my invention taken in the plane of line 1—1, Fig. 2.

Fig. 2 is a longitudinal sectional view of the same dry-kiln taken in the plane of line 2—2, Fig. 1.

Fig. 3 is an enlarged detail sectional view of one end of the steam supply pipe for the 60 steam distributing nozzles or blowers showing a portion of the handle for turning the pipe with the nozzles thereon for changing the direction of circulation of the steam and air.

Fig. 4 is a detail sectional view taken in the plane of line 4—4, Fig. 3.

Fig. 5 is an enlarged detail sectional view through the valve operating shaft taken in the plane of line 5—5, Fig. 2.

Fig. 6 is an enlarged detail sectional view through one of the steam nozzles and the adjacent portion of the steam pipe taken in the plane of line 6—6, Fig. 2.

As illustrated, this dry-kiln comprises upright side and end walls 1 and 2, and bottom and top walls 3 and 4 forming a drying chamber 5, a heating chamber 6 underlying the drying chamber and partially separated therefrom by a horizontal partition wall 7, 85 Figs. 1 and 2, and an air conduit 8 underlying the heating chamber and adapted to rest upon the bottom wall 3 of the housing.

The partition 7 constitutes a floor extending from end to end of the drying chamber 90 and heating chamber but is relatively narrower transversely than the corresponding width of said chambers to form air passages between its opposite longitudinal edges and opposite side walls of the housing as shown 95 more clearly in Fig. 1. This floor 7 is mounted upon suitable cross-beams 9 which are supported at their ends upon the side walls 1 and are adapted to support a pair of rails 10.

The rails 10 extend lengthwise of and with- 100

in the housing adjacent the opposite longitudinal edges of the floor 7 for supporting a carriage 11 upon which the lumber or other material to be dried is stacked in such manner as to allow circulation of the moisture-laden air around and between the several layers.

The end walls of the drying chamber are provided with openings of sufficient size to permit the passage of the carriage 11 with 10 the stack of lumber therethrough, said openings being normally closed by suitable doors 12 during the drying operation but may be opened at will to permit the carriage with the lumber therein to be moved into and out 15 of the kiln. (See Fig. 2.)

The side walls 1 of the housing are provided with upright air stacks or flues 13 arranged at suitable spaced intervals through 20 the length of the side walls and extending from the lower end of the drying chamber 5 above the upper end thereof to communicate with the atmosphere.

The lower ends of these air stacks or flues 25 13 are provided with openings 14 connecting them with the adjacent portions of the drying chamber, the openings at each side being controlled by a set of valves or dampers 15 which are mounted upon a suitable rock shaft 30 16 for simultaneous movement to and from their closed positions.

Each rock shaft 16 is journaled in suitable bearings 16' on the adjacent side wall 1 to extend through and beyond one of the end walls 35 where it is provided with a suitable hand crank 16" by which it may be rocked for opening and closing the corresponding series of dampers 15.

The outer end of each shaft is provided 40 with a toothed rack 17 having its teeth adapted to be engaged by a pawl or detent 18 which is spring pressed into engagement with the registering tooth of the rack 17 by a spring 19 to hold the dampers 15 on that particular shaft in its adjusted position and thereby 45 to closely control the volume of air passing through the openings 14 of the corresponding stacks 13 as may be required from time to time. (See Fig. 5.)

A heater 20 consisting, in this instance, of 50 a series of steam pipe coils are suspended from the floor 7 by hangers 21 within the heating chamber 6 or directly beneath the floor 7 and superposed drying chamber 5 to extend the major portion of the length of 55 said heating chamber but relatively narrower than the same to form air passages at opposite sides thereof connecting the heating chamber with the drying chamber.

The several sets of pipe coils of the heater 60 20 are connected at their opposite ends to suitable pipe-headers 22 and 22', the header 22 being connected to a steam supply pipe 23 leading from any available source of supply and provided with a valve 23' adapted to

be opened and closed at will, while the header 22' is connected to a delivery pipe 24 leading to a steam condensing trap or drainage not shown, and may be provided with a normally open valve 25 if desired.

The air-conduit 8 is mounted on the bottom 70 3 of the heating chamber 6 directly beneath the heater 20 and extends from end to end of the housing to register with air inlets 26 in opposite ends of said housing as shown in Fig. 2, for receiving external fresh air.

The intermediate portions of opposite sides of the conduit are provided at suitable intervals with additional air-inlet openings 27 to permit recirculation of the heated moisture-laden air and (or) fresh air through the 80 drying chamber when desired and in a manner presently described.

The air-conduit 8 is also provided in its upper side with a series of outlet openings 28 in longitudinally spaced relation for permitting the fresh air or recirculated vapor to pass through the overlying heating and drying chambers for moistening and drying the lumber in the drying chamber, the opposite side walls of each outlet being upwardly divergent to permit a relatively wide distribution of the heated air into said drying chamber.

A tubular rock-shaft 29 is journaled in suitable bearings 30 centrally within the lower portion of the conduit and extends the major portion of the length thereof across all of the outlet 28, one end of said rock shaft being closed while the other end extends through the adjacent opening 26 and is connected by a coupling 31 to a steam or other fluid pressure supply pipe 32 leading to any available source of supply not shown, for supplying steam to the interior of the rock-shaft.

The intermediate portion of the tubular rock-shaft 29 is provided with a series of axially spaced ejector nozzles or blowers 33 projecting radially therefrom into the outlet openings 28 to rock with said shaft for receiving steam therefrom and for discharging said steam in different directions and thereby changing the direction of circulation of the moisture-laden air through the drying chamber and lumber pile therein. (See Fig. 6.)

These ejectors or blowers 33 are preferably of the multiple nozzle type in which the nozzles gradually increase in capacity from the rock-shaft outwardly to afford a gradually increasing range of distribution of the escaping steam and also to gradually reduce its speed of circulation through the drying chamber but without interrupting the free and continuous flow of the vapor.

In Fig. 6 one of the ejectors or blowers is shown as comprising a T-coupling 34 connecting the adjacent ends of two sections of the rock-shaft and provided with a radially projecting nipple 35 upon which is mounted

70

a series of connected outwardly tapered nozzles 36 coaxial with the nipple 35 for receiving steam therefrom.

The diameters of the nipple 35 and nozzles 36 gradually increase from the rock-shaft outwardly for the purpose previously described, the larger ends of the nozzles 36 being united to and supported by the smaller ends of the next adjacent nozzle and provided with air-inlet openings 37 to allow the air or vapor to be drawn thereinto by suction of the steam jets to mingle with the steam in transit to the drying chamber.

The outer end of the rock-shaft 29 is provided with a hand-crank 38 for rocking the same with the ejectors or blowers 33 thereon through an arc of about 90° more or less for changing the direction of circulation of the moisture-laden air through the drying chamber, it being understood that the flaring sides of the outlets 28 permit this relatively wide range of movement of the nozzles, this movement being limited by suitable stops 39 adapted to be engaged by the hand crank 38 as shown in Fig. 4.

The dry-kiln shown may be used for cross-piling or end-piling compartment or progressive drying depending simply upon the length of the kiln and number of heaters and steam distributors used, it being understood that when a progressive or stage drying is required the kiln will be made of sufficient length to permit the movement of the lumber carrier to different positions therein and that in each different position the lumber may be subjected to different degrees of temperature and (or) different degrees of humidity.

A baffle plate 40 is suspended from the top wall 4 of the dry-kiln into the upper portion of the drying chamber 5 to extend from end to end of said drying chamber substantially midway between the opposite side walls of the kiln, as shown in Fig. 1, to prevent direct circulation of the heated vapor over the top of the lumber stack A and thereby to cause a more even distribution of the heated vapor between the several layers of the stack.

Operation

When one of the doors 12 is opened the carrier 11 with the stack of lumber to be seasoned and dried thereon is moved along the track 10 into the drying chamber 5 after which both of the doors are closed to retain the heat in said chamber.

The steam-controlling valve 23 may then be opened to admit steam to the heater coils 20 for heating the surrounding air and permitting the same to rise into the drying chamber for circulation between the several layers of lumber on the carrier 11.

The steam may be admitted to the tubular rock-shaft 29 and discharged through the several ejector nozzles or blowers 33 into the heating chamber 6 and thence into the

drying chamber to mingle with the heated air to accelerate circulation of the moisture-laden air between the several layers of lumber.

This introduction of the several jets of steam into the drying chamber causes the fresh air to be drawn from the outside of the kiln through the openings 26 into the conduit 8 and thence through the outlets 28 to mingle with the steam so that the mixture of air and steam will be forcibly circulated upwardly into the drying chamber and between the several layers of lumber, the moistened vapor serving to soften the texture of the lumber and thereby to liberate the inherent moisture and sap therefrom, it being understood that the steam-supply pipe 32 will be provided with a suitable controlling valve, not shown, for regulating the quantity of the steam admitted to the drying chamber.

It is also to be understood that the moisture-laden air when delivered to the drying chamber will be pre-heated by the heating coils 20 thereby increasing the humidity of the vapor for moisture and permitting the moisture and sap in the lumber to be carried off continuously by the circulation thereof between the several layers of lumber.

The direction of circulation of the vapor through the drying chamber may be varied at will by simply rocking the tubular shaft 29 with the blowers 33 thereon to different positions about the axis thereof through the medium of the hand-crank 38 thus permitting a relatively wide range of distribution of the vapor in different directions between the several layers of lumber in said chamber.

That is, when the blowers 33 are shifted to one extreme position as shown by full line in Fig. 1, the current of moisture-laden air will be directed upwardly across the corresponding side of the lumber stack A and thence through the several layers of lumber to return at the opposite side of said stack, the lateral deflection of the upwardly circulating currents of vapor between the several layers of lumber being aided by the use of the baffle plate 40.

On the other hand, if the blowers 33 are shifted to the other extreme position as shown by dotted lines in Fig. 1, the direction of circulation of the heated vapor will be reversed, it being understood that if the blowers are adjusted to an intermediate position, the circulation of the heated vapor will be directed across both sides of the lumber stack and will find its own direction of return.

It is evident from the foregoing description, that the adjustment of the blowers 33 to one extreme position or the other will establish and maintain a uni-directional circulation of the heated vapor through the drying chamber and that this uni-directional circulation may be varied at will by simply ad-

justing the blowers from one position to the other.

For example; if circulation of the vapor through the drying chamber is to be maintained in one direction, the dampers 15 in one of the side walls of the kiln may be closed and those in the opposite side walls may be opened to which conditions the blowers 33 would be adjusted to direct the circulation 10 therefrom toward the side of the wall having the closed dampers to enable the vapor to pass upwardly between the closed side and adjacent side of the lumber stack and thence transversely between the several layers of 15 said stack and return through the opened dampers to escape through the adjacent flues 13.

Again, if the vapor is to be re-circulated through the drying chamber as may be required in some conditions of the lumber, the dampers 15 in both of the side walls of the kiln will be closed thus allowing the vapor to pass upwardly from the blowers 33 into the drying chamber at one side of the lumber 20 stack and thence transversely between the layers of the lumber and return at the opposite side of the stack to the interior air-conduit 8 through the adjacent openings 27 for re-circulation of the same vapor together 25 with such quantities of fresh air as may be drawn into the conduit 8 through the openings 26.

This same uni-directional circulation or re-circulation of the heated air or vapor through 35 the drying chamber and lumber stack may take place without introducing steam or extra moisture through the ejector nozzles or blowers 33 by simply shutting off the supply of steam to the tubular shaft 29, it being 40 understood that when the uni-directional circulation is required, one or the other of the dampers 15 will be opened more or less to regulate the rapidity of circulation and that when both dampers are closed, the re-circulation 45 will follow.

It is, therefore, evident that the lumber in the same compartment may be dried in different stages or according to the condition of the lumber by regulating the quantity of 50 steam delivered through the blowers 33 or by shutting off the supply of steam to said blowers and relying primarily upon the heat produced by the heater coils 20 and admission of fresh air into the drying chamber through 55 the air-conduit 8.

It is also evident that by extending the length of the dry-kiln and duplicating the heaters and steam distributing blowers along the kiln at different positions, the unseasoned 60 lumber may be subjected to the circulation of moisture-laden air with the lumber-supporting carriage in one position and then moving the carriage with the lumber thereon to another position where the lumber may 65 be subjected to the circulation of air with a

reduced moisture content and finally to another position where the steam supply for moistening purposes may be shut off and the lumber subjected to heated air alone with such moisture content as may be contained 70 in the atmosphere admitted to the air-conduit 8, thus producing what may be termed a progress or stage drying of the lumber.

What I claim is:

1. A dry-kiln having a heating chamber, 75 a drying chamber above the heating chamber, a heater within the heating chamber, a fresh air conduit below the heating chamber having communication with the external air and provided with an outlet discharging into and through the heating chamber and means for projecting steam through the outlet for humidifying the air in transit from said conduit through the heating chamber and thence upwardly through the drying chamber, said 80 means being movable in opposite directions to different angles for changing its direction of circulation of the air and steam through said drying chamber.

2. A dry-kiln having a drying chamber, 90 means in the lower part of the said drying chamber for supporting the material to be dried, a heating chamber below the drying chamber, a heater within the heating chamber, an air conduit below the heating chamber 95 having an air inlet communicating with the drying chamber and an outlet discharging into the heating chamber and means for discharging steam through the outlet into the heating chamber and drying chamber for humidifying the air and to cause a return flow of the humidified air from the drying chamber into said conduit through the inlet, said means including a steam pipe rockable about its axis and provided with a plurality 100 of radial steam exits in its upper side.

3. A dry-kiln having a drying chamber, a heating chamber below the drying chamber, and an air conduit below the heating chamber, means for supporting the material to be dried within the drying chamber in spaced relation to opposite walls of the dry-kiln to form intervening air passages, said heating chamber having means for permitting the passage of air therethrough vertically and horizontally, a heater within said heating chamber, said air conduit having an inlet communicating with the external air and an outlet discharging into the heating chamber and means for projecting steam from the interior of the conduit upwardly through said outlet and into the heating chamber and drying chamber for humidifying the air and circulating it through the drying chamber, said means including a plurality of steam nozzles 115 tiltable to different angles for changing the direction of circulation of the humidified air.

4. A dry-kiln having a drying chamber provided with an air outlet in one of its side walls near the lower end thereof, an air stack 120

70

80

- connected to said air outlet and extended upwardly therefrom above the drying chamber, means within the dry-kiln for supporting the material to be dried, a heating chamber 5 below the drying chamber, a heater within the heating chamber, an air conduit beneath the heating chamber and provided with an inlet communicating with the external air, said air conduit having an outlet 10 discharging into the heating chamber and drying chamber and means for projecting steam through the outlet of the air conduit toward the wall of the drying chamber opposite the outlet of said drying chamber for 15 humidifying the air and causing it to circulate upwardly at one side of the material to be dried opposite of the outlet of the drying chamber and thence around and through the material to be dried and outwardly through 20 the outlet of the drying chamber to escape through said stack, said means including a steam pipe rockable about its axis and provided with a plurality of radial discharge nozzles.
- 25 5. A dry-kiln having a drying chamber, a heater for heating the air in the drying chamber, an air conduit beneath the drying chamber having an air inlet communicating with the external air and provided with an upwardly discharging outlet, and means for directing a fluid under pressure through the outlet for circulating the heated air through the drying chamber, said directing means being adjustable to change the direction of 30 flow of the pressure fluid and thereby to change the direction of the circulation of the heated air through the drying chamber.
- 35 6. A dry-kiln having a drying chamber, means for supporting the material to be dried 40 within said chamber, a heater below the drying chamber for heating the air therein, an air conduit beneath the heater having an air inlet communicating with the drying chamber and provided with an outlet in its upper side to permit the re-circulation of air from the air conduit to the drying chamber and return to the air conduit, and steam receiving means for directing steam from the interior of the air conduit through its outlet 45 to expedite the re-circulation of the air, said steam-receiving means including a steam pipe having an upwardly projecting nozzle movable in opposite directions to different angles for changing the direction of flow of 50 the steam and air through the drying chamber.
- 55 7. A dry-kiln having a drying chamber, means for supporting the material to be dried within said chamber, a heater below 60 the drying chamber for heating the air therein, an air conduit beneath the heater having an air inlet communicating with the drying chamber and provided with an outlet in its upper side to permit the re-circulation of air from the air conduit to the drying chamber
- and return to the air conduit, and means for directing steam from the interior of the air conduit through its outlet for humidifying the air and for re-circulating the humidified air through the drying chamber and return to the air conduit, said means including a steam nozzle movable to different angles for changing the direction of circulation of the steam and air through the drying chamber.
8. A dry-kiln having a drying chamber, means for supporting the material to be dried within said chamber, a heater below the drying chamber for heating the air therein, an air conduit beneath the heater having an air inlet communicating with the drying chamber and provided with an outlet in its upper side to permit the re-circulation of air from the air conduit to the drying chamber and return to the air conduit, and means for directing steam from the interior of the air conduit through its outlet for humidifying the air and for re-circulating the humidified air through the drying chamber and return to the air conduit, said steam directing means being adjustable to different positions for changing direction of circulation of the air through the drying chamber.
- In witness whereof I have hereunto set my hand this 1st day of May, 1929.
- HIRAM L. HENDERSON.
